ATTORNEY

UNITED STATES PATENT OFFICE.

SOPHIA FIEDLER, OF BOWDLE, SOUTH DAKOTA, ASSIGNOR OF ONE-HALF TO MARTIN T. ANDERSON, OF BOWDLE, SOUTH DAKOTA.

WINDOW-SCREEN.

1,282,206.

Specification of Letters Patent.

Patented Oct. 22, 1918.

Application filed April 16, 1917. Serial No. 162,421.

To all whom it may concern:

Be it known that I, SOPHIA FIEDLER, a citizen of the United States, residing at Bowdle, in the county of Edmunds and 5 State of South Dakota, have invented certain new and useful Improvements in Window-Screens, of which the following is a specification.

This invention relates to an improvement 10 in window screens and more particularly to a device of this character adapted to be fitted to a window without changing or modifying the construction thereof and so arranged that the screen proper is mounted upon a 15 roll to be moved over the window opening, or cleared therefrom.

An object of my invention resides in providing a supporting frame structure together with a roller on which the wire or 20 other screen fabric is to be taken up, and means by which the roller is actuated.

A further object lies in providing means by which the screen is held against being taken up by the roller and can be set in 25 various adjustments, and also means to draw in the side edges of the screen fabric to establish an insect proof closure at these points.

With the above and other objects in view, which will be in part described and in part 30 understood from the specification, drawing, and claims, my invention consists in certain novel features of construction and combinations of parts which will be hereinafter more fully set forth.

35 In the drawings:—

Figure 1 is a view in elevation of a device constructed after the manner of my invention;

Fig. 2 is a vertical sectional view taken 40 on the line 2—2 of Fig. 1;

Fig. 3 is a view similar to Fig. 2 but taken on the line 3—3 of Fig. 1;

Fig. 4 is a horizontal sectional view on the line 4—4 of Fig. 1;

Fig. 5 is a fragmentary detail view to 45 show the means for holding the screen strips being taken up by the roller; and,

Fig. 6 is a detail view to better disclose the arrangement of the structure for drawing in 50 the edges of the screen strip.

A frame structure generally designated by the reference character 1 is made up of angle iron or other suitable members and is of 55 rectangular form, this frame portion being of such size that it will fit within the casing

of the window and will have a snug fit entirely around its sides to thus preclude the possibility of insects finding their way through between the frame and the window casing. The frame structure may be made 60 of angle iron members, sheet metal strips, or of other suitable material, and is provided with vertically extending racks 2 at each side. A roller 3 is mounted in suitable bearings at the top of the frame portion 1 and 65 on one end has a spool or cable drum 4 provided, a tube 5 being in line with this spool or drum 4 and a weight 6 being mounted within the tube and carried on the free end 70 of a cable 7 which is connected on the spool or drum 4. A screen strip 8, which is of wire fabric or of other suitable material is mounted on the roller 3 and is carried down over the opening of the frame 1, a strip 9 being connected on the free edge thereof. 75 Slide bearings 10 and 11 are carried by this strip 9 and the rods 12 and 13 are slidably mounted in these bearings 10, the handle pieces 14 being provided on these rods, as is better shown in Fig. 5. The bearings 10 and 80 11 are so positioned on the strip 9 that the rods 12 and 13 have the outer ends thereof in proximity to the racks 2 and a coil spring 15 is mounted between the handles 14 around the inner ends of these rods 12 and 85 13 to normally urge the same outwardly so that the ends thereof will engage with the teeth of the rack portions 2. The outer ends of the rods 12 and 13 work through a guiding strip 12 secured to the inner face of 90 the screen 8, the strip 12 being suitably slotted to permit the operation of the rods 12 and 13 therethrough.

The screen strip is carried over an idler roller or a rod 16, and is thus kept 95 straight adjacent the roller 3, and a frame 17 is made of such size that it fits over the side edges of the screen strip after the manner shown in Figs. 1 and 2, this frame portion 17 being provided with a plurality of more or less resilient fingers 18, as 100 illustrated in Fig. 1. The frame portion 17 has a relatively loose mounting as it is carried by the links 19 which have pivotal mounting in the bearings 20 of the frame 17 105 and at their opposite ends are pivotally mounted on bearings 21 on the rods 22, of which one is provided for each side of the frame. These links 19 are received through slit-like openings 23 of the frame structure 110

1, and the rods 22 have rings 24 at the lower ends thereof so that these rods may be pulled down to draw the links 19 through the slit-like openings 23 and to draw in the frame portion 17 to such an extent that the more or less resilient fingers 18 thereof will bear against the side edges of the screen strip 8 and will thus close the side edges tightly against the frame portion 1 to positively exclude insects at this point. It is preferable that the frame 1 be mounted on the outer side of the window sashes, and when the screen is set with the strip 8 drawn or closed over the window, if it be desired to open the screen, the lower sash will be raised and the rods 22 will be released from their secured position which will permit the frame portion 17 to swing out sufficiently that the side edges of the screen strip are released from the clamped position, and then by grasping the handles 11 of the rods 12 and 13, and moving the same inwardly against pressure of the spring 15, the ends of the rods 12 and 13 will be disengaged from the teeth of the racks 2 as carried by the frame 1, in consequence of which the weight 6 will unwind the cable 7 from the spool or drum 4 and will turn the roller 3 in a direction to take up the screen strip, release of the handle 14 of course permitting the spring 15 to again shut out the rods 12 and 13 to engage with the teeth of the racks 2 and to thus positively secure the screen strip at any desired height. To again close the screen strip over the opening, the handles 14 will be moved in to release the rods 12 and 13 from engagement in the teeth of the rack 2, and then by putting downward pressure on the handles 14, the strip 9 as secured on the edge of the screen fabric strip will be moved down and the screen strip proper will be unwound from the roller 3 against the counter balance of the weight which will be raised through the fact that the cable 7 will be wound upon the spool or drum 4.

From the foregoing it will be seen that I have provided a screen structure which is of such character that it can be very inexpensively manufactured and can be installed for use in conjunction with windows of standard size and without the aid of special tools or the services of a skilled mechanic, and that while the structure is of such a character to accomplish a very efficient screening of the window opening, it is yet of such a simple nature that there is very little possibility of the parts becoming broken, misplaced or out of order; and, while I have herein shown and described only one specific form of construction, it will of course be understood that a number of changes and variations might be resorted to, in view of which fact I wish to be limited only to such points as may be set forth in the claims.

It should be understood that as the screen

is moved over the opening in the frame, the ends of the rods 12 and 13 may be secured within one of the notches formed in the bars 2 and the resilient fingers 18 are moved through the wire mesh screen so as to firmly clamp the wire mesh screen adjacent the edges thereof and hold the screen in a taut position. The fingers 18 may be moved easily through the wire mesh screen, by drawing the frame 17 inwardly, the fingers 18 being carried by the inner edges of the frame 17 and normally overhanging the outer face of the screen 8. When it is desired to again raise the screen, the fingers 18 may be moved out of engagement with the wire mesh screen, by forcing the frame 17 outwardly, and in this way the screen 8 will be released from the frame 17 and the fingers 18 and may be moved to the desired position upon the main frame 1.

I claim:—

1. A screen including a frame portion to be fitted within the opening to be screened, a screen strip movable within the frame, means to lock and hold the screen strip in adjusted positions to which it may be moved, means to take up the screen strip as the same is moved from the opening through the frame, means to exclude insects at the edges of the screen strip, and means to clamp down said last mentioned means to hold the screen strip against bulging.

2. A screen including a frame portion to be fitted in the opening to be screened, a roller carried by said frame structure at one extremity thereof, means by which force is normally exerted against said roller to turn the same in one direction, a screen strip connected with the roller and fitted to be moved across to cover the opening of the frame, and locking means by which the screen strip is locked to be held in various positions of extension across the opening of the frame until manually released.

3. A screen including a frame portion to be fitted in the opening to be screened, a roller carried by said frame structure at one extremity thereof, means by which force is normally exerted against said roller to turn the same in one direction, a screen strip connected with the roller and fitted to be moved across to cover the opening of the frame, means by which the screen strip is held in various positions of extension across the opening of the frame, a second frame mounted in conjunction with the first mentioned frame, and means to draw said second frame down against the side edges of the screen strip.

4. A screen including a frame portion to be fitted in the opening to be screened, a roller carried by said frame structure at one extremity thereof, means by which force is normally exerted against said roller to turn the same in one direction, a screen strip con-

nnected with the roller and fitted to be moved across to cover the opening of the frame, means by which the screen strip is held in various positions of extension across the opening of the frame, a second frame mounted in conjunction with the first mentioned frame, means to draw said second frame down against the side edges of the screen strip, and more or less resilient fingers carried by said second mentioned frame to exert pressure against the edges of the screen strip to positively force the same against the first mentioned frame and hold the strip against bulging and sagging.

15 5. A screen comprising a frame portion

adapted to be placed within an opening to be screened, a screen strip movably mounted within said frame, an outer clamping frame carried by said first mentioned frame portion, and means carried by said outer frame and adapted to extend between a mesh of said screen strip for firmly clamping the edges of said screen strip in engagement with said first mentioned frame portion.

In testimony whereof I affix my signature 25
in presence of two witnesses.

SOPHIA FIEDLER.
